UNITED STATES PATENT OFFICE

2,500,852

ROOM COOLER

Roland H. Money, Lima, Ohio, assignor to Art-kraft Manufacturing Corporation, Lima, Ohio, a corporation of Ohio

Application January 22, 1949, Serial No. 72,112

9 Claims. (Cl. 62—140)

1

This invention relates to a room cooler and dehumidifier.

This invention contemplates a room cooler which is of simple structure, cheap to produce, efficient in operation, and easily mounted upon, or removed from, the sill of a conventional window, such as a sliding sash type window, but my cooling unit can be used with hinged casement windows.

It is an object of the invention to produce a room cooler which is quiet in operation and this object is accomplished by mounting the motor compressor and condenser on the outside of the window. This arrangement also provides a simple and economical arrangement for dissipating the heat units into the outside atmosphere which have been extracted from the room being cooled.

The invention also contemplates a room cooler which is light in weight but of sturdy construction and which can be very easily and simply mounted in the window.

Fig. 1 is a vertical section through a window showing my room cooler in operative position.

Figs. 2 and 3 are sections along the lines 2—2 and 3—3 of Fig. 1.

Fig. 4 is a detail showing the mounting of the tubular frame on the window sill.

Referring more particularly to the drawings, there is shown a fragment of the room 1 which is to be cooled, having a floor 2, an outside wall 3, a sliding window sash 4, and a window sill 5.

My room cooler and dehumidifying unit comprises an inner housing 6 and an outer housing 7, each made of a light sheet metal such as aluminum. Housings 6 and 7 are integrally joined together by two spaced L-shaped tubular supports 8 and 9. Preferably tubular supports 8 and 9 are of square cross-section.

The outside housing comprises a perforated bottom wall 10, imperforate end walls 11, an imperforate top wall 12, and an imperforate front wall 13. Rear wall 14 can be imperforate but preferably is in the form of grill to facilitate circulation of the air over the condenser 15 and the motor compressor unit 16 which are mounted within housing 7. A conventional fan 18, driven by electric motor 19, is also mounted within housing 7 for circulating the air across condenser 15 and motor compressor unit 16.

Housing 6 is provided with an imperforate bottom wall 20 which is inclined downwardly toward the window sill 5. An evaporator 21 is positioned in the open front portion of housing 6 and a motor driven fan 22 is positioned within hous-

2

ing 6 in back of evaporator 21 for circulating the air from the room through evaporator 21. The end walls 23 and the rear wall 24 of housing 6 preferably, but not necessarily, are imperforate but the top wall 25 is preferably in the form of a grill to facilitate circulation of the room air by the fan across or through evaporator 21 and out of the open front of housing 6.

Tubular support members 8 communicate with the lower corners of housing 6 as at 26 and with the upper inner corners of housing 7 as at 27. The evaporator 21 communicates with the low or intake side of compressor unit 16 by means of tube 28 and the high or exhaust side of compressor 16 communicates with condenser 15 and condenser 15 communicates by means of tube or liquid line 29 with the inlet side of evaporator 21. It should be noted that the high compression refrigerant line 29 passes from the condenser 15 upwardly through tubular frame member 9 to the evaporator and that the low side or suction line 28 is housed within tubular frame member 8. Lines 28 and 29 can be housed in either one of tubular frame members 8 or 9, but preferably are housed separately, as shown.

The electric power line or cable 30 for conducting current to the motor compressor unit 16 and fan motor 19 also passes through one of the tubular frame members which, by way of example, is tubular frame member 8. In addition to serving as a housing for refrigerant lines 28 and 29, and power line 30, tubular frame members 8 and 9 serve as drainage tubes or conduits down which the moisture condensed from the air being cooled flows from inclined bottom pan 20 to back wall 14 of outer housing 7 on and through the perforate floor 10 of the outer housing 7.

A pair of rubber bumpers or supports 35 are mounted on the rear wall 14 of housing 7 adjacent the lower end thereof. These rubber supports or bumpers contact the outer face 36 of wall 3 to space housing 7 therefrom.

My room cooler unit is sufficiently light so that it can be easily manually lifted into and out of the window opening. To assemble my unit in the window opening, sash 4 is raised and the cooler unit is set in the window opening with the horizontal portions of tubular frame members 8 and 9 resting upon the upper face of sill 5 and with the housing 7 positioned outside the room, preferably out of doors, and the housing 6 positioned within the room. A pair of angle brackets 37 are secured by screws to the inner face of sill 5 and are provided with elongated openings 38.

A depending threaded stud 39 is welded on the outside of the bottom wall of each of the tubular frame members 8 and 9. These studs project through slots 38 and wing nuts 40 are threaded on the studs and when turned down clamp the frame members 8 to the angle irons 37 to hold the cooling unit in place. The elongated slots 38 permit the unit to be adjusted in and out on the window sill so that the rubber bumpers 35 will abut the outer face of wall 3 before wing nuts 40 are tightened down. After the cooler unit is in place, sash 4 is lowered with the bottom frame member 41 in contact with tubular frame members 8 and 9 and the transverse tubular frame member 42, which extends between frame members 8 and 9 and closes off the space between the bottom edge of window frame member 1 and the upper face of sill 5.

In the operation of my room cooler, the plug 43 will be plugged into any convenient socket outlet and the mechanical refrigeration unit will be set in operation. The refrigerant will be compressed in compressor unit 16, condensed in condenser 15, evaporated in evaporator 21, and returned to the compressor 16 through suction line 28, all in a conventional manner. However, the heat which is removed from the refrigerant in condenser 15 is not returned back to the room 1 but is dissipated to the atmosphere. The unit, of course, will be provided with all of the conventional controls, such as the room thermostat, float valve, etc. Preferably the liquefying restrictor which is conventional and may be an expansion valve or, as shown, a capillary tube 45, will be set so that the temperature of the evaporator will always be above freezing but well below the dew point. Consequently, the air being cooled, upon flowing through evaporator 21, will be chilled below the dew point and the condensed moisture will flow down inclined bottom wall 26 of housing 6 into tubes 8 and 9 and thence through the bottom wall 10 of housing 7 on to the ground without.

I claim:

1. A room cooler adapted for mounting on the sill of a window, comprising a frame adapted to set upon the window sill and a mechanical refrigeration apparatus mounted on said frame comprising an evaporator mounted on the end of said frame adapted to be positioned on the inner side of the window, a compressor and condenser mounted on the end of the frame adapted to be positioned on the outer side of the window, a suction line connecting the evaporator and the compressor, and a liquid refrigerant line connecting the condenser and evaporator whereby the heat which is taken up by the refrigerant in the evaporator is dissipated into the outside atmosphere by the condenser, said frame including a tubular load bearing member having a substantially horizontal portion adapted to rest upon the window sill and a downwardly projecting portion adapted for positioning on the outer side of the window sill, a drip pan below the evaporator and having a discharge end communicating with said tubular frame member whereby the condensation from the evaporator flows from the drip pan through the tubular frame member and is discharged on the outer side of the window.

2. The room cooler claimed in claim 1 wherein

at least one of said refrigerant lines passes through and is housed within said tubular frame member.

3. The main cooler claimed in claim 2 including an electric motor for driving said compressor, and an electric power supply line connected at one end to said motor and extending through said tubular frame member to the inner side of said window.

4. A room cooler adapted for mounting on the sill of a window, comprising a frame adapted to set upon the window sill and a mechanical refrigeration apparatus mounted on said frame comprising an evaporator mounted on the end of said frame adapted to be positioned on the inner side of the window, a compressor and condenser mounted on the end of the frame adapted to be positioned on the outer side of the window, a suction line connecting the evaporator and the compressor, and a liquid refrigerant line connecting the condenser and evaporator whereby the heat which is taken up by the refrigerant in the evaporator is dissipated into the outside atmosphere by the condenser, the said evaporator being positioned at a higher elevation than the condenser and compressor, said frame comprising a pair of spaced tubular members adapted to set upon the window sill, and a housing for the evaporator mounted on the ends of the tubular frame members adapted for positioning on the inner side of the window, and a housing for the compressor and condenser mounted on the ends of the tubular frame members adapted for positioning on the outer side of the window.

5. The room cooler claimed in claim 4 wherein the tubular frame members are substantially L-shaped having a horizontal portion adapted for setting on the window sill, and a vertically depending portion adapted for mounting on the outer side of the window sill.

6. The room cooler as claimed in claim 5 wherein the bottom wall of the inner housing is in the form of a drip pan inclined downwardly toward at least one of said tubular frame members whereby the condensate from the evaporator flows through the tubular frame member and is discharged on the outer side of the window.

7. The room cooler claimed in claim 6 wherein the liquid refrigerant and suction lines pass through and are housed within one or more of the tubular frame members.

8. The room cooler claimed in claim 7 including an electric motor for driving said compressor, and an electric power supply line for said motor passing through one of said tubular frame members and having a free end projecting from the inner end of the tubular frame member.

9. The room cooler claimed in claim 4 including means for attaching the frame member to a window sill.
